EJECTION-TYPE KEY RETAINER

Lowell Kniebes, Coloma, Mich.

Application May 15, 1950, Serial No. 161,944

4 Claims. (Cl. 70—414)

1

My invention relates to key holders or key retainers.

An important object of my invention is to provide a compact key retainer permitting interchangeability of keys; one that is provided with ejection mechanism to permit the key to be inserted into an operative lock to which it is fitted.

Another object of my invention is to provide spring means to urge the key and the key ejector mechanism, normally, in compacted arrangement concealing the key.

A further object of my invention is to provide an ejector-type key retainer of the aforementioned character which will maintain one or more keys compactly within its confines, make a key readily available for instant usage, and a mechanism which will protect the pockets of a garment from becoming torn by the rough portions of the key combination.

Another object of my invention is to provide means for readily interchanging keys and securing them to the ejector or slider mechanism provided on the key holder.

Other objects, ancillary features, and advantages to be derived from my invention will become readily apparent from a cursory examination of the accompanying drawings, taken in connection with the elucidation in the ensuing description, wherein like numerals are used to designate like parts, and in which:

Fig. 1 is a perspective view of my invention showing certain portions thereof cut away in section, in order to more clearly illustrate the elemental structure thereof.

Fig. 2 is a longitudinal cross-sectional view of Fig. 1.

Fig. 3 is a transverse cross-sectional view of Fig. 1 taken along the lines bisecting the rear roller supports of the structure.

Fig. 4 is a fragmentary sectional view showing the ejector in maximum ejected position to permit removal of a key therefrom, or to permit insertion of a key thereto.

Referring to the various views, my invention is generally designated 5, and consists of a case 6 having a slotted opening from end to end along the longitudinal axis thereof, providing a bottom portion 8 which is cut out arcuately as indicated at 9 in order to facilitate removal from, or assembly to, the ejector mechanism of keys as will appear hereinafter as the description progresses.

The top portion of the case 6 is provided with an elongated slot 17 to limit the ambital move-

2

ment of the ejector mechanism generally designated 11.

The ejector designated 11 is motivated within the confines of the slotted portion 17 heretofore mentioned, when the key designated 10 is to be ejected from the case 6 in order that it be inserted into a lock for opening or locking the said lock.

The ejector mechanism consists of a top portion designated 12 having a bored portion 14 for securing it to the lowermost section of the ejector designated 15, which has a protuberance or boss 16 fitted into the bored portion 14 on the lower surface 13, being held in place securely by the oval-head screw 27 having its threaded portion 28 secured to the boss portion 16 holding the unit firmly in place and assembly.

The slider has a guide portion 31 operating within the slot 17; a recessed portion 32 with a filleted enlargement is provided for snap engagement of the hollow rivet 18, which has a head portion 19 secured flush within the confines of the counter-sunk portion 20 in the bottom section 15 of the ejector 11. The said hollow rivet 18 is provided with slotted portions 18' terminating in the enlarged openings 30 in order to provide resilience to the lip 29 so that it may engage in snapping relationship with the filleted portion 32.

The key 10 has a hole in it which is mounted on the hollow rivet 18.

The boss portion 16 is provided with an arcuate cut-out portion 33 in order to locate the spring 21 firmly in place. The spring 21 is of endless construction and has portions of its peripheral portion mounted in triangulated arrangement over the boss portion 16 and the arcuate cut-out portion 33 and the rollers generally designated 25. The said rollers also are provided with locating reduced filleted portions 26 so that the spring will be confined in its place in triangulated arrangement as heretofore mentioned. The rollers 25 facilitate the movement of the spring in its elongation and contraction depending upon the forward movements of the ejector structure 11, or its return to normal position.

The tubular elements, or bushings 25, are pivoted about the oval head screws 22 provided with an enlarged shoulder portion 23 acting as a guide for the bushings or tubular members 25 and a reduced threaded portion 24 so as to hold the bushings 25 in place.

It is to be noted that the bushings 25 are slightly shorter in length than the height of the slot 7 so as to permit their free rotation whenever the spring 21 is actuated.

In order to insert or remove a key it is necessary to bring the ejector 11 to its outermost position in the slot 17, hold it there, firmly in place, to permit grasping the head 19 of the hollow rivet 18 by the fingers of the hand, since the arcuate opening 9 affords clearance therefor, so that the rivet 18 may be pulled out disengaging the lip 29 from the filleted portion 32, whence the key 10 may be removed, or a new key inserted, hollow rivet 18 subsequently being forced back into place whereby its lip 29 will engage in snap relationship the filleted portion 32. The ejector is then allowed to assume its normal position by actuation of the spring 21 and the unit is ready for use. When the key 10, mounted within the unit, is to be utilized, the ejector is forced outwardly against the tension of the spring 21 to its outermost position in the slot 17, then the key operating portion 34 extends beyond the confines of the case 6, and may be inserted into the lock for locking or unlocking operations.

After the key has been used for its intended purposes, the ejector mechanism is released and it returns to normal position so as to conceal the key within the casing 6.

The knurled portion 35 is provided to facilitate actuation of the ejector mechanism when the key is to be exposed outside of the confines of the casing 6.

It is to be understood that changes may be made in the construction and in the combination and arrangement of the several parts, provided that such changes fall within the scope of the appended claims.

Having thus disclosed and revealed my invention, what I claim as new and desire to secure by Letters Patent is:

1. A pocket key retainer, comprising a case provided with a slotted opening longitudinally therethrough and an elongated slotted portion on its top surface, ejector means slidably mounted in the said case and provided with guide means operatively associated with the said elongated slotted portion and having a top portion extending beyond the width of the said slotted portion, hollow rivet means removably secured to the said ejector means adapted to support removably a key thereon, bushing means rotatably mounted within the confines of the said slotted opening and located at one end of the said case, and endless spring means interconnecting the said bushing means and the said ejector means to maintain the said ejector means normally in retracted position.

2. A pocket key retainer, comprising a case provided with a slotted opening longitudinally therethrough and an elongated slotted portion on its top surface, ejector means slidably mounted in the said case and provided with guide means operatively associated with the said elongated slotted portion and having a top portion extending beyond the width of the said slotted portion, hollow rivet means removably secured to the said ejector means adapted to support removably a key thereon, bushing means rotatably mounted within the confines of the said slotted

opening and located at one end of the said case, and endless spring means interconnecting the said bushing means and the said ejector means to maintain the said ejector means normally in retracted position, the said bushing means and the said ejector means being provided with filleted portions to locate the said spring means in fixed position.

3. A pocket key retainer, comprising a case provided with a slotted opening longitudinally therethrough and an elongated slotted portion on its top surface, ejector means slidably mounted in the said case and provided with guide means operatively associated with the said elongated slotted portion and having a top portion extending beyond the width of the said slotted portion, hollow rivet means removably secured to the said ejector means adapted to support removably a key thereon, bushing means rotatably mounted within the confines of the said slotted opening and located at one end of the said case, and endless spring means interconnecting the said bushing means and the said ejector means to maintain the said ejector means normally in retracted position, the bottom surface of the said case being provided with an arcuate cut-out portion to facilitate removal of the said hollow rivet means for interchangeability of keys to be mounted thereon.

4. A pocket key retainer, comprising a case provided with a slotted opening longitudinally therethrough and an elongated slotted portion on its top surface, ejector means slidably mounted in the said case and provided with guide means operatively associated with the said elongated slotted portion and having a top portion extending beyond the width of the said slotted portion, hollow rivet means removably secured to the said ejector means adapted to support removably a key thereon, bushing means rotatably mounted within the confines of the said slotted opening and located at one end of the said case, and endless spring means interconnecting the said bushing means and the said ejector means to maintain the said ejector means normally in retracted position, the said bushing means and the said ejector means being provided with filleted portions to locate the said spring means in fixed position, the bottom surface of the said case being provided with an arcuate cut-out portion to facilitate removal of the said hollow rivet means for interchangeability of keys to be mounted thereon.
